UNITED STATES PATENT OFFICE.

JOHN W. KITTREDGE, OF AKRON, OHIO.

HOISTING BLOCK.

Application filed May 14, 1921. Serial No. 469,457.

My invention relates particularly to an attachment to hand power chain blocks to prevent their being overloaded. Chain blocks are used for lifting heavy weights and their first and foremost requirement is absolute safety. It is well known, however, that through carelessness and ignorance very many blocks are at some time loaded beyond their proper working strength, thereby 5 breaking them or injuring them so as to make them unsafe thereafter.

The objects of my invention are:—

1st. To provide a block with holding mechanism to hold it against backward movement, and with the parts between the holding mechanism and the lifting wheel, of gearing or other positive mechanism, so that there can be no possibility of the load slipping.

2nd. To provide a release between the driving wheel and the holding mechanism which shall automatically release at a certain forward torque on the driving wheel, thereby rendering it impossible to lift a 25 load beyond the working strength of the block.

3rd. To have the release such that while it will not raise an excessive load, it will lower it to the floor, should such excessive load come upon the block through accident or any means other than the block's own lifting mechanism.

4th. To have the said release such that it will automatically grip and lift its proper load as soon as the excessive load is relieved.

5th. To have all parts simple and protected from accidental injury.

I have shown in the drawings a spur geared block with the brake of my co-pending patent application No. 356,235; but my invention can be applied to worm blocks, to hoists with direct drive, to those with screw and ratchet brakes, to power driven hoists and to a great variety of other types. The "holding mechanism" may be the lifting mechanism, as in the case of the worm block, or it may be an independent brake as here-with shown.

I attain the foregoing objects by the mechanism shown in the accompanying drawings, in which:—

Fig. 1 is a longitudinal section on line

E—E of Fig. 2; and Fig. 2 is a transverse section on line A—B—C—D of Fig. 1, with 55 the plate 45 and the nut 46 removed.

Parts fastened rigidly together are cross-hatched alike, even though they may be separate pieces of metal. For clearness of description, a given part is designated by a 60 numeral, as 47, and different edges or faces of that part by that numeral with letters, as 47^A, 47^B, etc. A given piece carries the same number throughout the several views.

The block is hung from an overhead support by the hook 1, which is attached to the gear case 2 and the brake case 3 by the swivel bar 4. Bolts 25 and spacers 26 bind the cases firmly together. A lifting sprocket 5 is journaled in bearings in the cases 2 70 and 3, and it carries a lifting chain 6 and a lifting hook 39. The arrows, in every case, indicate the parts running in the direction to lift the load. The drive shaft 9 passes centrally through the lifting sprocket 5 and is journaled in bearings therein. The wheel 8 with its lug 8^A turns freely on the drive shaft 9 through a partial revolution. Lug 8^A actuates the lever 31, and lever 31 in turn actuates the drive shaft 9 to which it is 80 rigidly keyed. The drive shaft 9 actuates the lifting sprocket 5 and the lifting chain 6 through the planetary gearing shown in Fig. 1 and common in chain block construction.

The lever 31 is connected to the internal brake band 29 by the lever 34 and the shoes 32 and 33. The wheel 8 and lug 8^A collapse the band and cause it to turn freely; but the load on hook 39, acting through the 90 drive shaft 9, expands the band against its enclosing walls and causes it to bind and hold the load.

Integral with the wheel 8 is the threaded portion 8^B. The wheel 47 has a corresponding threaded portion 47^B engaging 8^B. Integral also with the wheel 47 is the lug 47^A. A stud 48 is set in the wheel 8 and extends through a slot in wheel 47. A spring 49 extends from the lug 47^A to the stud 48 and tends to screw the wheels 8 and 47 closely together. The sprocket 50 fits against a beveled friction surface on wheel 47 and against a ball bearing 51 on wheel 8, and is firmly gripped between them by virtue of 100 the screw and the spring 49. The sprocket

50 carries the hand chain 7. The plate 45 is simply a protecting cover.

The operation of the block is as follows:—

The operator pulls the chain 7 in the direction of the arrow, and thereby actuates the sprocket 50. Sprocket 50 binds with wheel 47 through heavy friction and turns it arrow-wise. Wheel 47 through lug 47^A, spring 49 and stud 48 turns wheel 8 arrow-wise and, within the strength of the spring 49, these parts all move together as a single rigid piece. And wheel 8, through its lug 8^A, lever 31, drive shaft 9, sprocket 5 and the connecting gears, actuates the chain 6 and the hook 39 and lifts the load. When, however, the load is excessive, the wheel 8 and the stud 48 remain stationary. As the operator then pulls the chain 7 arrow-wise, the sprocket 50 turns on the ball bearing 51 and turns wheel 47 with it through friction; the spring 49 yields; and the wheel 47 screws away from the wheel 8 until the friction between wheel 47 and sprocket 50 is sufficiently relieved to allow sprocket 50 to slip.

By making the spring 49 of proper strength, it will transmit torque sufficient to lift a proper load, but will yield within the working strength of the block and prevent overloading. When the excessive load is relieved, the spring 49 at once expands, screwing the wheel 47 tightly down on the wheel 8, causing heavy friction between wheel 47 and sprocket 50, and again transmitting sufficient torque to lift a proper load.

Suppose now that an excessive load should be put upon the block through independent means; as that it should be hooked to the block and then the supports taken from beneath it. It would act upon the sprocket 5, the gearing, the drive shaft and the brake, and these would hold it positively to the limit of their strength. The slip member, being beyond the brake, would not affect the holding in any way whatsoever. It would, however, prevent lifting the load higher as just described. Suppose now, the operator, finding the load excessive, wishes to lower it to the floor. He pulls the chain 7 counter-arrow-wise. The chain pull, as well as the force of the spring, tends to screw the wheels 47 and 8 together, firmly gripping the sprocket 50; and he thus lowers the load to the floor.

The maximum forward torque on the driving wheel 50 is controlled by the spring 49, the strength of which is approximately constant, and not by the coefficient of friction which is widely variable. Suppose two blocks with springs 49 equal to each other; the first with oil on the friction surfaces of wheel 47 and sprocket 50; the second with said surfaces dry and rusted. On the first, slipping will occur when the pressure be-

tween the surfaces is very great; on the second, the two parts will turn together until the screw has relieved the pressure, and it is small. In other words, the larger the coefficient of friction, the smaller will be the pressure, and their product, which controls the slip, will be approximately constant.

Similar construction can be applied to hoists and blocks of other types as hereinbefore described.

In the following claims, the word "between" is intended to have reference to the sequence of the driving operations, and not to physical position. For instance, if the driving member 50 actuates the clutch members 47 and 8, and the member 8 then moves the friction member 29, the members 47 and 8 are said to be "between" the driving member 50 and the friction member 29, even though they should not be between them in physical position.

Having thus described my invention, I claim as new and desire to secure by Letters Patent:—

1. In combination, a hoisting block comprising a driving member, a driven member, said driven member adapted to carry a load, a drive connection from said driving member to said driven member, friction members between said driving and driven members adapted to hold the load through friction against backward movement, and friction clutch members between the driving member and the said friction members, the arrangement being such that backward torque upon the driving member causes the clutch members to grip, but that a given forward torque upon the driving member causes the clutch members to release, and means causing the clutch members to grip automatically whenever the torque on the driving member is less than the given torque aforesaid.

2. In combination, a hoisting block comprising a driving clutch member, a driven clutch member, a driven wheel, said driven wheel adapted to carry a load, a drive connection from said driven clutch member to said driven wheel, friction members adapted to control an element of the said drive connection in its backward rotation, the drive connection from the controlled element to the driven wheel including positive driving elements, the arrangement being such that backward torque upon the driving clutch member causes the clutch members to grip, that a given forward torque upon the driving clutch member causes the clutch members to release, and that the clutch members grip automatically whenever the torque on the driving clutch member is less than the given torque aforesaid.

3. In combination, a hoisting block comprising a driving member, a driven mem-

ber, a drive connection therebetween, a brake adapted to retard an element of the said drive connection against backward rotation, said drive connection from the retarded element to the driven member being positive driving members, and a slip clutch in the said drive connection.

4. In combination, a hoisting block comprising a driving member, a driven member, a drive connection from the driving member to the driven member, a brake, said brake retarding an element of the said drive connection against backward rotation, the said drive connection from the said retarded element to the driven member being positive driving members, a friction clutch in the said drive connection between the driving member and the said retarded element, a spring in the said friction clutch, and connecting means whereby it exerts pressure between the friction surfaces of the clutch and whereby the forward torque of the driving member tends to relieve the said pressure.

5. In combination, a hoisting block comprising a driving wheel, a drive shaft, a driven wheel, a positive drive connection from the drive shaft to the driven wheel, a friction brake, a connection from the brake to the drive shaft, a drive connection from the driving wheel to the drive shaft through the said brake connection, a friction clutch in the said last mentioned drive connection, and a spring in the said friction clutch adapted to exert pressure between the friction surfaces thereof.

6. In combination, a hoisting block comprising a driving member, a driven member, a clutch member, the clutch member being in frictional engagement with the driving member, a positive drive connection from the clutch member to the driven member, a screw on the clutch member whereby said clutch member tightens or loosens its frictional engagement with the said driving member, a spring acting on the said clutch member, the direction of the screw being such that the spring tends to tighten the said frictional engagement and the forward torque of the driving member tends to loosen it.

7. In a hoisting block, the combination of a screw-threaded clutch member, a second clutch member, said clutch members having cone surfaces in engagement, a spring adapted to turn the screw member and thereby tighten the engagement between the said cone surfaces to a driving frictional engagement, said direction of tightening being opposite to the direction of drive whereby the driving torque tends to loosen the said frictional engagement, a driven wheel controlled in its backward rotation, and a positive drive connection from the driven clutch member to the driven wheel.

8. In combination, a hoisting block comprising a driving wheel, a driven wheel, a gear drive adapted to drive the said driven wheel, driving means from the driving wheel to an element of the said gear drive, a friction clutch in the said driving means, a spring in the said friction clutch adapted to exert pressure between the friction surfaces thereof and to yield at a given forward torque of the driving wheel and thereby relieve the said pressure, a brake, connecting means from the brake to an element of the said gear drive whereby backward torque of the said element tends to set the brake and forward torque of the said element tends to release the brake, and means whereby backward torque of the driving wheel tends to release the said brake.

9. In combination, a hoisting block comprising a drive shaft, a driven member, a gear connection from the drive shaft to the driven member, a friction brake, a positive connection from the brake to the drive shaft, friction clutch elements, spring means adapted to press the said clutch elements into driving frictional engagement and to yield at a given forward torque of the driving clutch element and thereby release the clutch elements, and a drive connection from the driven clutch element to the drive shaft through the brake connection.

10. In combination, a hoisting block comprising a friction clutch mechanism, spring means in the said clutch mechanism adapted to press the friction surfaces thereof into driving frictional engagement, a lifting mechanism, said lifting mechanism comprising a lifting wheel, a planetary gear train, a drive shaft thereto, and a brake, and a drive connection from the driven clutch element through said brake to the shaft.

11. In combination, a hoisting block comprising a driving wheel, a driven wheel, a planetary gear train adapted to drive the said driven wheel, a drive shaft connected to the said planetary gear train, driving means from the driving wheel to the said drive shaft, a friction clutch in the said driving means, a spring connected to the driven clutch member, means whereby it exerts pressure between the members of said clutch and whereby the forward torque of the driving wheel reduces the said pressure, a brake, and a direct connection from the brake to the drive shaft.

12. In a hoisting block, the combination of a driving sprocket, a driven sprocket, a lifting chain fitted to the driven sprocket, a clutch wheel bearing on one side of the driving sprocket through a friction contact, a second wheel bearing on the opposite side of the driving sprocket with less friction therebetween than in the friction contact of the clutch wheel, a screw connection between the two said wheels, a spring connection be-

4
tween the two said wheels tending to screw them together, the direction of the screw such that the forward torque of the driving sprocket tends to screw the two said 5 wheels apart, and a positive drive connection from the second wheel to the driven sprocket.

13. A hoisting block comprising a driving sprocket, a driven sprocket, a clutch 10 wheel bearing upon one side of the driving sprocket through a friction contact, a second wheel bearing upon the opposite side of the driving sprocket through a ball bearing, a screw connection between the two said 15 wheels whereby their pressure on the driving sprocket may be increased or diminished, a spring connection between the two said wheels tending to screw them together and thereby increase their pressure on 20 the driving sprocket, the direction of the screw such that the forward torque of the driving sprocket tends to screw the two said wheels apart and thereby diminish their pressure on the driving sprocket, and a positive drive connection from the second wheel 25 to the driven sprocket.

14. In a hoisting block, the combination of a frame, a driving member, a driven member, a drive shaft, a planetary gear connection from the drive shaft to the driven member, an annular wall on the said frame, a brake band within said wall and in frictional engagement therewith, a lever, a connection from the lever to each end of the 30 brake band, a connection from the lever to the drive shaft, a drive connection from the driving wheel to the drive shaft through the last named connection, and an overload release in the said drive connection.

40 15. In combination, a hoisting block comprising a driving member, a driven member, a gear drive adapted to drive said driven member, driving means from the driving member to an element of the said gear drive, a friction clutch in the said driving means, a spring in the said friction clutch adapted to exert pressure between the friction surfaces thereof and to yield at a given forward torque of the driving member and thereby relieve the said pressure, a brake, and positive connecting means from the brake to an element of the said gear drive whereby backward torque of the said element tends to set the brake and forward torque of the said element tends to release the brake.

50 16. In combination, a hoisting block comprising a drive shaft, a driven member, a positive drive connection from the drive shaft to the driven member, a friction brake, a positive connection from the brake to the drive shaft, a driving clutch member, a driven clutch member, spring means in the driven clutch member causing it to grip the driving clutch member and on a given for-

ward torque of the driving clutch member to release the said member, and a drive connection from the driven clutch member to the drive shaft through the said brake connection.

70 17. In combination, a hoisting block comprising a driven member, a planetary gear train adapted to drive said driven member, a brake, a positive connection from the brake to an element of the said planetary gear train whereby the brake controls the said element in its backward rotation, a friction clutch, spring means in the said friction clutch adapted to press the friction surfaces thereof into driving frictional engagement, 80 and a drive connection from the driven clutch element to an element of the planetary gear train through the brake connection.

75 18. In combination, a hoisting block comprising a driven member, a planetary gear train adapted to drive said driven member, a brake, a positive connection from the brake to an element of the said planetary gear train whereby the brake controls the said element in its backward rotation, a friction clutch, spring means in the said friction clutch adapted to press the friction surfaces thereof into driving frictional engagement and to yield at a given forward torque of the driving clutch element and thereby relieve the said pressure, and a drive connection from the driven clutch element to an element of the planetary gear train through the brake connection.

85 90 19. In combination, a hoisting block comprising a drive shaft, a driven member, a positive drive connection from the drive shaft to said driven member, a brake, a positive connection from the brake to the drive shaft, a clutch with cone surfaces in frictional engagement, spring means in said clutch adapted to press the cone surfaces into driving frictional engagement and on a given forward torque of the driving clutch element to release the said pressure, and a drive connection from the driven clutch element to the drive shaft through the said brake connection.

95 100 105 110 20. In a hoisting block, the combination of a drive shaft, a driven member, a positive drive connection from the drive shaft to the driven member, an internal band brake, positive connecting means from the band brake to the drive shaft whereby backward torque of the drive shaft sets the brake and forward torque of said shaft releases the brake, a friction clutch, spring means in the said clutch adapted to press the friction surfaces thereof into driving frictional engagement and to yield at a given forward torque of the driving clutch element and thereby relieve the said pressure, a drive connection from the driven clutch element to the drive shaft through the said brake connection, and means whereby back-

ward rotation of the clutch releases the said brake.

21. In a hoisting block, the combination of a driving sprocket, a driven sprocket, a lifting chain fitted to a driven sprocket, a clutch wheel bearing on one side of the driving sprocket through a friction contact, a second wheel bearing on the opposite side of the driving sprocket with less friction 5 therebetween than in the friction contact of the clutch wheel, a screw connection between the two said wheels, a spring connection between the said wheels tending to screw them together, the direction of the screw 10 such that the forward torque of the driving sprocket tends to screw the two said wheels apart, a drive connection from the second wheel to the driven sprocket, a brake adapted to control an element of the said drive 15 connection in its backward rotation, and the 20

said drive connection from the controlled element to the driven sprocket being positive driving element.

22. In a hoisting block, the combination of a friction clutch mechanism, screw elements therein, a spring connection between the said screw elements whereby the said elements press the clutch surfaces into driving frictional engagement, a driven wheel, a drive connection from the driven clutch element to the driven wheel, a brake adapted to control an element of said drive connection in its backward rotation, and the said drive connection from the retarded element to the driven wheel comprising positive driving elements. 25 30 35

In testimony whereof, I have signed my name to this specification this 5th day of May, 1921.

JOHN W. KITTREDGE.
